METHOD AND APPARATUS FOR SPINNING
ARTIFICIAL FILAMENTOUS PRODUCTSRobert J. Taylor, Claymont, Del., assignor to
American Viscose Corporation, Wilmington,
Del., a corporation of Delaware

Application July 3, 1943, Serial No. 493,404

9 Claims. (Cl. 18—8)

1

This invention is a modification of the methods and of the apparatus of my copending applications Serial No. 479,889, filed March 20, 1943, now Patent 2,399,258, Serial No. 439,071, filed May 27, 1943, now Patent 2,399,259, and Serial No. 490,009, filed June 8, 1943, now Patent 2,399,260, and is particularly concerned with the production, processing, and collection of continuous filamentary materials while maintaining them in the form of a thin web-like sheet in which the component filaments exhibit a considerable degree of intercrossing though generally extending in the direction of the length of the sheet. In my copending applications, there are disclosed arrangements of apparatus and methods of spinning continuous artificial filaments in the form of a multiple-filament bundle which is collected within the spinning bath while condensing the multiple-filament bundle along one direction only so that it is wound, with or without traverse, as a series of convolutions of a thin web-like sheet. The wound band, comprising the convolutions of the web-like sheet upon itself, is slit transversely of its annulus, laid out in a flat condition, dried and then stretched with respect to its width while maintaining longitudinal tension along its two sides. In both of such earlier applications, the subsequent drying and expansion of the dried wound band with respect to its width gives rise to novel products of extremely light-weight and fluffiness which are useful as heat insulation, cushioning material, buoyant material and the like.

In accordance with the present invention, there is provided a novel arrangement of apparatus which makes it possible to subject filaments spun in one bath to an after-stretching to effect further reduction in diameter of the filaments therein, or to any other processing treatment in a separate bath, and such transfer and treatment in the second bath is made while maintaining the filaments in the form of a web-like sheet which may comprise a plurality of layers of intercrossing filaments. This is especially important when dealing with extremely fine diameter filaments because such filaments are generally severely damaged if attempts are made to transfer them about solid guide surfaces to the second bath or, if it is desired to collect the filaments as a web-like sheet, to re-open a condensed yarn-like bundle thereof. While the particular conditions and the particular materials disclosed for use in executing the method will be described hereinafter with particular reference to the spinning of hydrophobic synthetic linear polymers, it is to be un-

2

derstood that the apparatus is applicable as well to the spinning of other materials such as cellulose acetate, viscose, and the like.

In the drawing, illustrative of the invention, Figure 1 is a perspective view showing somewhat diagrammatically the arrangement of the apparatus for carrying out the invention.

Figure 2 is a side elevation of the form of channel communicating between the coagulating bath and the stretching bath, and

Figure 3 is a plan view of the channel of Figure 2.

As shown in Figure 1, the coagulating bath is retained within a container or chamber 2 within which the spinneret 3 is shown immersed. A second container or chamber 4 whose walls may merely be extensions of those of the container 2 as shown and which is separated from the coagulating bath by the partition 5 serves to receive

20 a plasticizing liquid for the particular filaments to be after-stretched or any other desired processing liquid. The partitions 5 between the coagulating chamber 2 and the after-stretching chamber 4 is provided with a horizontally elongated aperture 6 adapted to receive a communicating channel 7 having a flared mouth 8 and a flared discharge end 9 which is preferably at least as large in diameter as its mouth. As shown in the drawing, particularly in Figure 2,

30 the vertical dimension of the passage through the channel 7 decreases from the mouth 8 to produce a relatively narrow constricted passage at the point of or in the vicinity of the passage through the partition 5 between the two chambers 2 and

35 4. A funnel guide 7b may be placed in the coagulating bath just in advance of the spinneret to control the waving motion of the filamentary material when it is composed of extremely fine diameters.

40 A guide roller or drum 10 whose peripheral surface has a width at least wide enough to accommodate the web-like sheet of the filaments guided thereby is mounted for rotation with the shaft 11 which is mounted in bearings (e. g., that indicated at 12) at such a height above the container that the guide roller 10 is partially immersed in the bath and its lowermost peripheral line is approximately in line with a funnel guide 7a placed in advance of the discharge end 9 of

45 50 the communicating channel 7 between the coagulating and after-stretching bath. A similar guide roller 13 is mounted for rotation in an opposite direction with its surface substantially in contact or at least very close to the peripheral surface of the first guide roller 10. The bearings

12 and 14 for the shafts 11 and 15 carrying the rollers 10 and 13 may be supported upon a common base plate 16 which may be provided with a slot 17 to permit adjustment of such rollers with respect to the supporting base or frame 18 so that the first guide roller may be positioned at any selected distance from the guide 1a. A take-up drum 19 may be arranged above the second guide roller 13 with its peripheral surface close to that of the roller 13 but sufficiently displaced therefrom to permit the desired thickness of band to be wound on the take-up drum 19 without interference from the roller 13. The take-up drum 19 may be arranged for axial traverse, if desired. A suitable driving arrangement may be provided for driving the take-up drum 19, as well as the first and second guide rollers 10 and 13 so that the web-like filamentary sheet has a constant linear speed in proceeding from the stretch bath to the take-up drum 19. Such driving arrangement may comprise a chain connection between sprockets on the take-up drum shaft and the first guide roller and gears connecting the shafts 11 and 15.

If desired, the guide rollers 10 and 13 may be omitted and the take-up device 19 may be positioned so that it runs partially immersed in the stretch bath and it may or may not be traversed with respect to the guide 1a. Again, the second roller guide 13 may be omitted and the take-up device 19 placed in close proximity to the first roller guide 10 in which event it may be operated with or without traverse.

The stretch bath may be provided with an overflow pipe 26 connecting with a reservoir 27 provided with a heating coil 28 to control the temperature and a pump 29 may introduce the liquid from this reservoir into the stretch bath at the desired rate by way of pipe 30. Since a certain amount of the liquid from the coagulating bath finds its way into the stretch bath through the communicating channel 7, provision may be made to redistribute the amount of liquid thus carried over, such as by an overflow pipe 31 within the reservoir 27 connected to a second reservoir 32 for the coagulating bath. This reservoir 32 may be provided with a heating or cooling jacket 33 to control the temperature and a pump 34 is provided to deliver from the reservoir coagulating liquid to the bath at the desired rate. Additional heating such as coils 35 may be placed in association with each of the baths, if desired.

As an example illustrating the use of the apparatus hereinabove described, a spinning solution in acetone of watery consistency of a copolymer of vinyl chloride and vinyl acetate may be extruded through a spinneret having 3000 holes into a coagulating bath in chamber 2 having a temperature between 35° and 50° C., preferably about 45° C. and is passed as a web-like sheet through the communicating tube 7 into chamber 4 containing an after-stretching bath having a temperature between 60° C. and 90° C., preferably about 80° C. The passage of the web-like sheet through the liquid, and particularly through the gradually narrowing portion of the channel 7 results in the exertion of a drag upon the filaments which oppose the force exerted by the guide roller 10 for withdrawing the sheet from the stretch bath. An additional factor in the exertion of drag upon the filaments in opposition to the withdrawing action of roller 10 is the difference in hydrostatic head between the baths 4 and 2, the liquid level in bath 4 being normally maintained at a higher elevation to reduce the

flow of liquid from the coagulating bath 2 into bath 4 through the channel 7. The result of these two factors is an effective controlled amount of stretching which may be adjusted by adjusting the distance of the guide roller 10 from the guide 1a, the greater the distance the greater the amount of stretching. Besides varying the distance, variation in the temperature of the after-stretch bath and the rate of travel of the filaments therethrough may be resorted to in order to obtain any desired effect.

10 The tapered construction of the channel 7 serves to provide an effective drag on the filaments and also reduces the amount of liquid transferred from the coagulating bath into the stretch bath. By providing a discharge opening at 9 of the same size as the entrance 8 to the channel 7, turbulence is controlled within the channel.

15 While the heat of hot water serves as a plasticizer for the vinyl resin filaments of the example, other plasticizers, swelling agents, and the like may be used in the stretch bath depending on the particular material of which the filaments are made, such as a mixture of water and acetone for cellulose acetate. Examples of other treating or processing liquids are washing liquids, desulphurizing liquids for filaments regenerated from viscose, waterproofing agents, and other conditioning liquids for imparting a desired finish or hand to the filaments.

20 In the foregoing description, reference is made for illustrative purposes, to the application of the invention for the production of mats of the type disclosed in my earlier applications. The invention is equally applicable to the transfer of filaments as a yarn-like bundle into a second bath and treatment of the bundle therein as such. In this event, the width of the aperture 6 may be correspondingly reduced.

25 While preferred embodiments of the invention have been disclosed, it is to be understood that changes and variations may be made without departing from the spirit and scope of the invention as defined by the appended claims.

30 I claim:

35 1. In apparatus for spinning artificial filaments, a receptacle for a coagulating liquid adapted to receive the liquid at least up to a predetermined level, a spinneret disposed therein below the predetermined level, a second receptacle for a treating liquid disposed in advance of the first receptacle and adapted to receive the liquid at least up to a predetermined level, a channel communicating directly between a region in each receptacle which is below the predetermined liquid level therein, said channel having a portion gradually narrowing with respect to its vertical dimension only and having a gradually widening portion beyond the narrowing portion, and rotatable means extending partially beneath the predetermined liquid level in the second receptacle for drawing and stretching the filaments while maintaining them in the general form of a web-like sheet from the spinneret through the channel into the second receptacle.

40 2. In apparatus for spinning artificial filaments, a receptacle, a transverse partition dividing it into two sections, one section for receiving a coagulating liquid at least up to a predetermined level and the other for receiving a treating liquid at least up to a predetermined level, a spinneret in the former of the sections below the predetermined level therein, a channel 45 extending through the partition below the pre-

determined liquid levels, said channel having a portion gradually narrowing with respect to its vertical dimension only and having a gradually widening portion beyond the narrowing portion, and means extending partially beneath the predetermined liquid level in the second section of the receptacle for drawing the filaments while maintaining them in the general form of a web-like sheet from the spinneret through the channel into the second section of the receptacle.

3. In apparatus for spinning artificial filaments, a receptacle, a transverse partition for dividing it into two sections, one for receiving a coagulating liquid at least up to a predetermined level and the other section for receiving a treating liquid at least up to a predetermined level, a spinneret in the former of the sections below the predetermined level therein, a channel extending through the partition below the predetermined liquid levels, said channel having a portion gradually narrowing with respect to its vertical dimension only and having a gradually widening portion beyond the narrowing portion, the discharge opening of the channel being at least as large as the entrance opening thereof, and means extending partially beneath the predetermined liquid level in the second section of the receptacle for drawing the filaments while maintaining them in the general form of a web-like sheet from the spinneret through the channel into the second section of the receptacle.

4. The method of making artificial filamentous products comprising extruding a spinning material through a plurality of orifices into a body of coagulating liquid to form a plurality of filaments therein, withdrawing the filaments from the position of extrusion under conditions of turbulence causing the paths of the filaments to overlap each other irregularly as viewed in a vertical direction and then passing the filaments while maintaining them in submerged relationship into a second body of liquid contiguous with the first without permitting the filaments to make substantial contact with solid guiding surfaces and while condensing the filaments to a web-like sheet, and collecting the filaments by winding them while still in the form of a web-like sheet, the entire passage of the filaments from the position of extrusion up to a position well-advanced in the second liquid body being effected without permitting the filaments to make substantial contact with solid surfaces.

5. The method of claim 4 in which the filaments are subjected to an increase in tension in the second body of liquid.

6. The method of claim 5 in which pressure within the second body of liquid is greater than that within the first liquid body at their position of contiguity whereby a flow of liquid occurs

countercurrent to the filaments and contributes to said increase in tension.

7. The method of making artificial filamentous products comprising extruding a spinning material through a plurality of orifices into a body of coagulating liquid at about 45° C. to form a plurality of filaments therein, withdrawing the filaments from the position of extrusion under conditions of turbulence causing the paths of the filaments to overlap each other irregularly as viewed in a vertical direction and then passing the filaments while maintaining them in submerged relationship into a second body of liquid contiguous with the first and having a temperature of 60° C. to 90° C. without permitting the filaments to make substantial contact with solid guiding surfaces and while condensing the filaments to a web-like sheet, subjecting the filaments to an increase in tension in the second body of liquid, and collecting the filaments by winding them while still in the form of a web-like sheet, the entire passage of the filaments from the position of extrusion up to a position well-advanced in the second liquid body being effected without permitting the filaments to make substantial contact with solid surfaces.

8. The method of claim 7 in which the spinning material is a solution of a vinyl resin copolymer.

9. The method of claim 8 in which the resin is a copolymer of vinyl chloride and vinyl acetate.
